UNITED STATES PATENT OFFICE.

CHARLES E. BUELL, OF NEW HAVEN, CONNECTICUT.

COMBINED TELEGRAPH AND CLOCK SYSTEM.

SPECIFICATION forming part of Letters Patent No. 279,327, dated June 12, 1883.

Application filed March 15, 1882. (No model.)

To all whom it may concern:

Be it known that I, CHARLES E. BUELL, of the city and county of New Haven, State of Connecticut, have invented new and useful 5 Improvements in a Combined Telegraph and Electric-Clock System, of which the following is a specification.

My invention relates to combining electric clocks and communicating-telegraphs upon 10 one and the same normally-closed electric circuit in such a manner as to give more certainty and accuracy than has been heretofore obtained in transmitting time over circuits of considerable length, and to the transmission 15 of time-signals and telegraphic signals by such means that they will not conflict with each other; and it consists in the combination, with a main electric circuit, of a controlling-clock, a series of clock-stations, each of which is provided with a clock which depends for the 20 progressive movement of its hands around the dial upon the action of a local circuit, or made operative by the action of a relay included in the main circuit and adapted to respond only 25 to the action of the controlling-clock, which may vary the tension of the circuit or reverse the currents charging the circuit, preferably the latter mode.

My invention further consists in the combination, upon the same normally-closed electric circuit used to actuate and control a series of electric clocks through the intermediate action of relays adapted to respond to reversals of the currents charging the circuit, of two or 35 more relays with neutral armatures, and adjusted to respond to rapid variations of the tension of said main circuit.

My invention further consists in certain novel combinations and sub-combinations, which 40 will be more fully described hereinafter.

Figure 1 represents the pendulum C' of a regulator-clock arranged to open and close the circuit of the local battery L B by passing its point into and out of the mercury contained 45 in the dish d, the action of the local circuit reversing the currents charging the main line by the intermediate operation of the circuit controlling magnet C M, which is described in my previous application.

50 I do not confine myself to the mode of re-

versing the currents upon the main circuit, shown herewith, as other and well-known methods may be substituted for the one shown; and I am aware that the currents may be reversed upon the main line without the intermediate controlling-magnet.

Fig. 2 represents an outlying station in which a clock and a telegraphic apparatus are combined to work separately or simultaneously without conflicting with the operation 60 of either. The telegraph-relay N R has a neutral armature, and is of ordinary construction, and is adapted to respond to variations of the tension of the circuit (by a distant station) by means of the retractile spring and condenser, the condenser serving to dissipate the retained magnetism which is observable in magnets included in a circuit whose tension is varied, and which is prolonged in its cessation, and an obstacle to sharp action of the relay, 70 unless dissipated by the condenser or its well-known equivalents. The resistance R is an adjustable resistance normally out of circuit. The key is of ordinary construction, and arranged to interpose the resistance in and withdraw it from the main circuit when manipulated for transmitting telegraphic signals thereby. The action of the neutral armature of the relay N R opens and closes the circuit of the local battery L B² for making operative 80 a sounder electro-magnet, which may be of ordinary construction and adjustment, the local circuit of battery L B² being shown in dotted lines. Although a sounder of ordinary construction may be employed, I have shown a 85 preferred form having two helices of insulated wire upon each leg of the magnet-core. The clock C' is operated by a magnet in a second local circuit, L B³, when the armature of relay P R is changed in its position by the reversals 90 of the currents charging the circuit, which occurs at predetermined periods by the action of pendulum C' (shown in Fig. 1, and described,) and by its action operating the clock or clocks C². As the reversals of the current upon the 95 main circuit tend to weaken, if not rupture, the contact of the armature of the relay N R and make it possible to produce false signals, I have passed a circuit from local battery L B³ through the lower helix of the magnet S M. 100

This circuit is, however, shunted away from the magnet S M when the armature of relay P R is in the position shown. As the polarized armature of the relay P R will start from its contact before the neutral armature will rupture its contact and the sounder-magnet S M respond, the current of local battery L B³ is passed through the extra helix of the sounder-magnet, retaining it and preventing false vibrations or signals. In Fig. 2 the circuit of local battery L B³ is shown over broken lines through the key and over the armature of relay N R and following spring s, which preserves contact during a partial break due to reversals of the current upon the line, but which does not preserve the contact when the relay-armature is fully retracted.

I am aware that the sounder-magnet S M and electric clock C² may be operated from one local battery.

Fig. 3 represents a central station, as shown in Fig. 1, and described, with way-stations 1, as shown in Fig. 2, and described, and way-station 2, like that shown in Fig. 2, except in the arrangement of the circuit from the local battery L B³, which in this view is shown as passing from the local circuit as a derived circuit without passing through the key and over the neutral armature of relay N R.

Fig. 4 represents a railway-station. The clock C² is shown above the platform and in view of passengers and passing trains, the telegraph apparatus in the station being included in the same main circuit with the clock-controlling relay, as shown in Fig. 2, and described, the telegraph-office being looped into the line in the ordinary manner, the key being, however, in the shunt-circuit around an adjustable resistance, for varying the circuit-tension in transmission, the relay P R for actuating the clock C² being contained in the case with the clock, and the local batteries L B² and L B³ placed at convenient points and connected by suitable wires, as shown in Fig. 2, and described.

By this mode of combining electric clocks and a telegraph system upon one normally-closed main line, messages may be sent and standard time indicated with certainty at each station without the signals of one sort conflicting with the proper transmission and production of the other signals.

I do not confine myself to the devices and arrangement of circuits and devices for carrying my invention into practice as shown here-with.

I reserve the right to claim in another application any improvement disclosed in this application and not now claimed.

What I claim as my invention is—

1. A main line, a battery or batteries for charging said main line, a regulator or controlling clock, and devices for transmitting time-signals over said main line at predetermined intervals, a series of stations along said main line, each provided with a transmitting-key, a relay electro-magnet and a sounder electro-magnet in a local circuit adapted to transmit and receive telegraphic signals, and a clock at each station adapted to be regulated to correct time by the said transmitted time-signals, whereby the said clocks at stations may be adjusted to correct time over a line used for message-telegraphs.

2. The combination, with a main electric circuit and devices adapted to automatically transmit time-signals over said circuit, of a series of stations, each provided with a transmitting-key and relay electro-magnet adapted, respectively, to transmit and receive telegraphic signals, and a clock at each station adapted to be made operative by a local circuit, and devices whereby said clock is regulated to correct time by said transmitted time-signals through the intermediate action of said local circuit, substantially as described.

3. The combination, with a main circuit and devices for automatically transmitting time-signals over said circuit without interrupting the continuity of said circuit, of a series of stations, each provided with a relay electro-magnet, a sounder electro-magnet for receiving and a key for transmitting signals other than time-signals, and apparatus at each station adapted to respond to said transmitted time-signals for controlling a clock at each, substantially as described.

CHARLES E. BUELL.
